COMBINED FOOD STORAGE AND CAFETERIA COUNTER UNIT

Delmar D. Rhoads, 3230 S. Calhoun St.,
Fort Wayne, Ind.

Filed June 9, 1958, Ser. No. 51,261

Term of patent 14 years

(Cl. D14—3)

FIGURE 1 is a perspective view of a combined food storage and cafeteria counter unit showing my new design;

FIGURE 2 is a top view thereof;

FIGURE 3 is a side elevational view thereof;

FIGURE 4 is a rear elevational view thereof;

The side opposite that shown in FIGURE 3 is substantially like the side shown.

The front not shown is substantially plain.

I claim:

The ornamental design for a combined food storage and cafeteria counter unit, substantially as shown and described.
